MOULDED PULP PACKING AND METHOD FOR PRODUCING SAME

Erik Louis Hartmann, Tvaervej, Birkerod, Denmark, assignor to Skandinavisk Emballage Aktieselskab, Lyngby, Denmark, a joint-stock company

Filed Jan. 17, 1964, Ser. No. 338,420

Claims priority, application Denmark, Mar. 12, 1963, 1,133

4 Claims. (Cl. 229—2.5)

The invention relates to a moulded pulp packing, especially a packing of this kind adapted to contain a number of eggs or other fragile or delicate objects, consisting of two parts, hinged together and constituting a lower part and an upper part, which parts when folded together enclose the objects, and of a locking flap hinged to the lower part. When this flap is in an inwardly swung position in which it is situated internally in the upper part a projection on the flap engages a corresponding aperture in the lateral wall of the upper part and locks the two parts together.

For technical reasons packings of this kind are manufactured in open or unfolded condition. The suction mould employed in the manufacturing process must be so arranged that the blank absorbed on the mould can be released from the latter in the same manner as known in connection with cast iron. In practice, the requisite inclination of all surfaces rising from the base of the mould is so adapted that the packings formed, after drying, can be nested, i.e. piled closely together. This property is easily obtained as far as the lower part and the upper part of the packing are concerned, but difficulties are encountered with the locking flap, because the locking projection on this flap, which during production is usually situated at the level of the base of the mould where there is unintentionally imparted an increased thickness of material, and because it has on the outer side, an inclination smaller than that of the other inclining surfaces of the packing. When such packings are nested, the locking flaps of packings following one another will therefore form a fan, which ultimately prevents further piling.

When packings are produced by machines from which the blanks in moist and therefore plastic condition are deposited on the plane surface of a conveyor, by which means they are passed through a drying kiln, the said surface must constitute a support for the blanks so as to preserve the shape imparted to them by the suction moulds. In order to be certain that the smoother surface is produced on the outer side of the packing and also in order to provide the most effective support, the blanks are so deposited on the conveyor that the lower side of the lower part and the upper side of the upper part will rest on the conveyor. In that case the locking flap which, in known packings, is on a level with the adjacent surfaces of the lower part and the upper part will have no support, so that it will be subject to buckling or to permanent deformation during the passage of the blank through the kiln, which may necessitate a subsequent pressing of the whole blank.

An object of the present invention is to provide such a locking flap construction that it does not adversely influence the nesting of the packings.

Another object of the invention is to provide a flap structure preventing it from being deformed during the passage of the blanks through the drying kiln.

A further object of the invention is to provide a locking flap so shaped that it is easily produced on suction moulds and has a locking projection which furthermore ensures a safe locking.

A still further object of the invention is to provide a method for producing moulded pulp packings having the above properties.

2

According to the invention, the packing is produced with a locking flap occupying an outward oblique position and having a free edge portion lying in the plane of the bottom of the lower part.

5 When this packing blank is deposited on the conveyor the free edge portion of the flap will come to rest on a plane surface in the same way as the lower part and the upper part, and therefore, the flap will be well supported during the drying of the blank.

10 It is expedient that the free edge portion of the locking flap be reinforced by means of an outwardly protruding ledge, which forms such an angle with the flap proper when in a downwardly oblique position that the ledge is located in the plane of the bottom of the lower part.

15 By this means a particularly good support for the flap is provided and also a bracing against deformation.

It is preferred that the flap proper and the ledge adjoin along a waved curve in the plane of the ledge in order to reduce the possibility of a swinging movement of the ledge 20 in relation to the flap proper during drying.

According to the invention the flap is provided with at least one projection shaped like a downwardly open nose, of uniform thickness and with a recess or opening therebelow, the width of which preferably increases towards the hinge edge of the flap.

25 Other characteristic features of the invention and the advantages derived therefrom will appear from the following description, reference being had to the accompanying drawings.

30 The drawings illustrate an embodiment of the packing designed to contain ten eggs, placed in two rows. The lower part of the packing has a shape which is specially designed for this purpose. It is emphasized, however, that the invention is not dependent on this design of the 35 lower part, since it can be applied to other packings which are constructed of two parts hinged together, irrespective of their shape. Still, the invention is most suitable for packings in which the upper part is shaped as a trough with plane base and oblique lateral wall inclining at the slip necessary for the moulding of the blanks and the nesting of the packings.

In the drawings:

FIG. 1 is a view of the packing from above, in unfolded condition;

45 FIG. 2 is a cross sectional view taken on the line II—II in FIG. 1 showing the packing in closed condition and on an increased scale; and

FIG. 3 is a broken front view of the packing in closed condition showing the locking arrangement.

50 The packing according to the invention is produced by precipitating fibre pulp by suction on a mould having a reticulated or perforated surface, in such a manner that substantially the same thickness of material is applied to all portions of the packing.

55 The packing, as shown in the drawings, comprises a lower part 10, an upper part 12 and a locking flap 14. The upper part 12 and the flap 14 are integral with the lower part 10 and hinged to its opposite sides by means of fold lines 16 and 18, which act as hinges. A number 60 of depressions 20 are provided in the lower part 10, each of which is designed to receive one end of an egg. The design of the lower part is otherwise determined by the need for providing the requisite strength and rigidity, which, however, is not relevant to the present invention.

65 The upper part 12 of the packing is provided with an oblique lateral wall 22 having an undulating outline arranged to fit around the outer surfaces of the upper portions of the eggs as shown in FIG. 1, and a flat top wall 24. The upper and lower parts are provided with edge flanges 26 which abut against one another when the packing 70 is closed, except along the front, as shown in FIGS.

2 and 3, where the flange 26 along the front of the upper part 12 abuts against a flange 27 of the flap 14.

The flap 14 comprises an oblique wall 28 extending upwardly from its flange 27 and having the same undulating outline as the part of the lateral wall 22 of the upper part 12 overlying the flap 14, and a ledge 30 forming an angle with the wall 28, equal to the angle between the top 24 and the oblique lateral wall 22 of the upper part 12, as shown in section in FIG. 2.

For the purpose of locking the said packing in closed condition there are provided on the locking flap 14, as shown in FIGS. 2 and 3, two spaced projections 32 cooperating respectively with rectangularly-shaped apertures 34 in the adjacent lateral wall 22 of the upper part 12. The locking projections 32 are located at the free edge portion of the flap 14, where it adjoins the ledge 30, as shown in FIG. 2 of the drawings.

Each projection 32 is shaped like a nose or a lip, open at the bottom, having an inclining front wall 36 (FIG. 2) and two parallel lateral walls 38. A U-shaped reinforcement in the form of an encircling external bead 40 is provided along the lower outside edge portions of the inclining wall 36 and the side walls 38.

A recess or opening 42 is provided or left in the oblique wall 28 of the locking flap 14 below each projection 32 for facilitating the release of the packing blank from the mould. The width of the openings 42 increases from the bottom of the beads 40 toward the fold line 18 or flange 27 as shown in dotted lines in FIG. 3. The openings 42 also provide weakened areas in the locking flap which facilitate the movement of the projections 32 inwardly to release the upper portion of the packing. The shape and location of the openings 42 facilitate removal of the packings from the mould, since the openings are left in the packing by being formed around projecting portions of the mould which have portions extending along the lower faces of the beads 40. At the end of a moulding operation, the projecting part of the mould extends through the opening 42. The mould, of course, includes projecting portions over which the locking projections 32 are formed.

When the packing is to be closed, the locking flap 14 is swung about the fold line 18 from the dotted line position shown in FIG. 2, upwardly and inwardly into the position shown in full lines, whereupon the upper part 12 is swung about the fold line 16 upwardly and inwardly, until it comes to rest against the lower part 10 and the flange 27. During the last phase of this movement the front of the lateral wall 22 of the upper part under the openings 34 will be forced outwardly and thereupon spring back, the projections 32 simultaneously engaging the respective openings 34. An internal reinforcing bead 44 is provided at the lower edge of each opening 34 over which the projections 32 slide. In locked condition the ledge 30 of the locking flap 14 extends along the lower side of the plane top 24 of the upper part, as shown in FIG. 2.

The shape of the projections 32 herein described as a downwardly open nose or lip makes it possible to make the thickness of the material of the projections the same as that of the other parts of the packing, and when the packing is produced with the locking flap 14 in the position shown in dotted lines in FIG. 2, the flap forms no obstacle to the nesting of the packings.

Having now fully described my invention I claim as new and desire to secure by Letters Patent:

1. In a moulded pulp packing including a hollow lower

part and an upper cup-shaped part having an oblique lateral wall so as to be readily releasable from the mould in which the packing is formed, said parts being hinged together with a lower edge of the upper part hinged to an upper edge of the lower part, and a locking flap hinged by its lower edge to the upper edge of the lower part opposite the position of the hinge between the upper and lower parts, said locking flap extending upwardly within and along the oblique wall of the upper part when it is in closed position and including a locking projection co-operating with an opening in said oblique wall of the upper part to lock the packing in closed condition when the upper part is brought over the lower part and the locking flap, and in which the locking projection is located at the upper portion of the locking flap, said locking flap being provided with a recess therein extending downwardly from the lower edge of the locking projection, and an outwardly-projecting reinforcing bead extending around the lower edge of the locking projection.

2. A moulded pulp packing as claimed in claim 1, in which the locking projection includes front and side walls and opens at the bottom into said recess, and in which said bead extends from the face of the locking flap on one side of the locking projection to the face of the locking flap on the other side of the projection.

3. In a moulded pulp packing including a hollow lower part and an upper cup-shaped part having an oblique lateral wall so as to be readily releasable from the mould in which the packing is formed, said parts being hinged together with a lower edge of the upper part hinged to an upper edge of the lower part, and a locking flap hinged by its lower edge to the upper edge of the lower part opposite the position of the hinge between the upper and lower parts, said locking flap extending upwardly within and along the oblique wall of the upper part when it is in closed position and including a locking projection co-operating with an opening in said oblique wall of the upper part to lock the packing in closed condition when the upper part is brought over the lower part and the locking flap, and in which the locking projection is shaped like a downwardly open nose and is located at the upper portion of the locking flap, said locking flap being provided with a recess therein extending downwardly from the lower edge of the locking projection.

4. A moulded pulp packing as claimed in claim 3, in which the locking projection includes front and side walls and opens at the bottom into said recess, and an external reinforcing bead encircling the lower free edge of the locking projection, said bead extending from the face of the locking flap on one side of the locking projection to the face of the locking flap on the other side of the projection.
